SOAP HOLDER

Mary Mildred Wessel, 2810 Meadow Drive,
Louisville, Ky.

Filed Jan. 14, 1963, Ser. No. 73,149

Term of patent 14 years

(Cl. D4—3)

FIG. 1

FIG. 2

FIG. 3

FIG. 4

FIG. 1 is a view in perspective of a soap holder embodying my new design;

FIG. 2 is a view in perspective from the back thereof;
FIG. 3 is a vertical sectional view taken along lines 3—3 of FIG. 1; and

FIG. 4 is a front elevational view thereof.

I claim:

The ornamental design for a soap holder, as shown.
